UNITED STATES PATENT OFFICE.

EDWARD B. GARDNER, OF BELOIT, WISCONSIN, ASSIGNOR TO BADGER TOOL COMPANY,
OF BELOIT, WISCONSIN, A CORPORATION OF WISCONSIN.

RING-GRINDING MACHINE.

Application filed December 9, 1920. Serial No. 429,299.

To all whom it may concern:

Be it known that I, EDWARD B. GARDNER, a citizen of the United States, residing at Beloit, in the county of Rock and State of Wisconsin, have invented certain new and useful Improvements in Ring-Grinding Machines, of which the following is a specification.

This invention relates in general to grinding machines, and more particularly to machines adapted for grinding or finishing the lateral edges of piston rings, although it may be used for operating upon other objects for similar purposes.

One of the primary objects of my invention is to provide a machine of the character indicated, which will simultaneously and automatically finish both sides of a piston ring uniformly and accurately so that the finished rings will all be of the same thickness and finish.

Another object of the invention is to provide novel means for holding the piston rings and conveying to and from the grinding tools, which means is adapted to freely rotate so that the rings will be rapidly rotated or spun by the grinding tools during the grinding operation to thus impart a better and more uniform finish than would be secured if the rings were stationarily held during the grinding operation.

Other features of the invention reside in the provision of means for retaining the rings on their respective holders during their travel toward and from the grinding tools, and in the provision of means for automatically stopping the spinning or the rotation of the rings after they are withdrawn from the tools, in order that they may be removed from the holders and replaced by other rings with a minimum consumption of time.

Other objects and many of the attendant advantages of my invention will be appreciated as the same becomes better understood by reference to the following description, when considered in connection with the accompanying drawings.

Referring to the drawings:

Fig. 1 is a side elevation of a machine embodying my invention;

Fig. 2 is a transverse sectional view taken between the grinding tools, and substantially on the line 2-2 of Fig. 1; and

Fig. 3 is a fragmentary view substantially on the line 3-3 of Fig. 1.
The grinding machine itself, to which the mechanism adapting it for the grinding of piston rings, is attachable, may be of any well known or preferred construction of double spindle machine, but for purposes of illustration in this instance, I have selected a grinding machine, the detailed construction of which is fully shown and described in co-pending application, Serial No. 426,857, filed November 26, 1920. Referring to the grinding machine generally, and to such details thereof only as will be necessary to an understanding of my present invention, it will be observed from Fig. 1 that the machine comprises a base 5, upon the top of which two carriages 6 and 7 respectively are mounted to slide longitudinally of the frame toward and from each other. In the carriage 6 is journaled a shaft 8 carrying at one end a grinding tool 9, and similarly in the carriage 7, there is journaled a shaft 11 carrying a grinding tool 12, arranged in opposed relation to the tool 9. The shafts 8 and 11 are rotated to revolve the tools 9 and 12 in the same direction by any suitable driving means, and the shafts may be directly connected to motors or driven by means of belts 10 and 20 from any suitable source of power.

The carriages are moved on the frame to bring the grinding tools into operative relation with a ring disposed between them so that both faces of the ring will be operated upon simultaneously by the tools and are intermittently withdrawn from each other to permit the insertion of a new ring and the withdrawal of a finished ring from between them, by any suitable mechanism. In the present instance, the carriage 6 is equipped with a depending rack 13 constantly meshing with a pinion 14 mounted upon a transversely extending shaft 15, and the carriage 7 has an arm 16 pivotally connected thereto and provided at its free end with a rack 17 also adapted to mesh with the pinion 14. The rack 17 is held in mesh with the pinion by a cam or other means mounted upon a shaft 18, which may be adjusted to engage the rack with, or disengage it from the pinion by means of an adjusting handle 19. The shaft 15 is rotated in a clockwise direc-

tion to move the grinding tools toward each other into grinding position by means of a weight 21 suspended from a lever 22 fixed to the shaft, and the shaft is rotated in a 5 counterclockwise direction against the influence of the weight 21 by means of a lever 23 fixed to the shaft and provided at its outer end with a follower 24 adapted to be intermittently actuated by automatic mechanism which will be later described, whereby 10 upon movement of this lever upwardly a separating movement is imparted to the grinding tools. Each grinding tool has a ring of abrasive material adjacent its periphery, as indicated by reference character 25, the radial thickness of this ring being such that a piston ring when disposed in position to be operated upon by the tools, extends completely across the width or radial 20 thickness of the abrasive material so that this material is worn down evenly instead of being peripherally grooved by the wear resulting from the grinding as it would be if the ring did not extend entirely across the 25 grinding face.

The front of the machine is equipped with a face plate 26 provided with an undercut slot 27, and to which is secured by bolts 28 an upwardly extending bracket or standard 29. The upper end of this standard is provided with an elongated journal bearing 31, in which is journaled a shaft 32 having fixed on one end thereof, a gear wheel 33, and on the opposite end, a disc-shaped carrier 34. This carrier is provided near its perimeter with a plurality of bearings 35, in each of which is rotatably mounted a short shaft 36, carrying at one end in proximity to the face of the carrier, a disc or 40 holder 37, adapted to receive a piston ring, indicated by 38, which is placed in position thereon by being slipped over the holder. The opposite end of each shaft 36 has secured thereon a collar 39, by which the shaft 45 is held against longitudinal displacement, these collars also serving as brake drums for a purpose which will be later explained.

The carrier is adjustable longitudinally of the machine frame by reason of a bolted 50 connection to the base plate 26 so that when properly adjusted, the plane of the holders 37 lies intermediate the grinding tools 9 and 12, and when the tools are caused to approach each other, the ring positioned 55 upon that holder which projects between the tools, is subjected to the action of the two grinding tools which finish the lateral surfaces of the ring. The holders 37 are, of course, thinner than the ring, so that they 60 are not ground down by the action of the tools upon the ring.

A rotary movement equal to the spacing between adjacent ring holders is imparted 65 to the carrier 34 intermittently to bring the holders with the rings thereon successively

into position between the grinding tools to be operated upon thereby. The mechanism for accomplishing this intermittent movement of the carrier comprises a shaft 41 journaled in suitable bearings upon the 70 front of the machine and constantly driven by a belt 42 or other suitable driving mechanism. Upon the shaft 41, there is mounted a sector gear 43 adapted to mesh at each revolution of the shaft 41 with the gear 33, 75 whereby at each revolution of the shaft 41, a quarter revolution is imparted to the carrier.

In order that the carrier may be locked against accidental movement during the 80 grinding operation upon each ring, I have provided an automatic locking mechanism comprising a locking pin 44 normally urged by a spring 45 into engagement with the locking notches 46 formed in the periphery 85 of the carrier. These notches are so positioned that one of them may be brought into alignment to receive the locking pin 44 just as the sector gear 43 leaves or ceases to mesh with the gear 33. For the purpose of releasing the pin 44 from locking relation with the carrier just prior to re-engagement of the gear 33, I have mounted upon the shaft 41 a cam 47, which, upon each revolution of the shaft engages the outer end 48 90 of a lever 49 fulcrumed at 51 on the frame of the machine and connected at 52 by pin and a slot connection with the locking pin 44.

Upon the shaft 41, there is also mounted 100 a cam 53 in the path of the follower 24 carried by the arm 23, and this cam is so designed and positioned that substantially simultaneously with the releasing of the locking pin 44, this cam elevates the lever 105 23 to thereby, through the rack and pinion connections, withdraw the carriages 6 and 7 with the grinding tools 9 and 12 from each other. During the time that the tools are held apart, the collar is indexed to 110 withdraw the finished ring and introduce another ring between the tools, whereupon when the carrier is again locked with a pin 44, the cam 53 travels from beneath the follower 24, permitting the tools to be moved 115 together again into grinding relation with the positioned ring by means of the weight 21, as previously explained. The requisite distance is maintained between the grinding tools by means of stop mechanism including 120 a stop bar 54 mounted on the carriage 7, and which co-operates with an adjustable abutment stop on the carriage 6 to thereby limit the approach of the tools. The details of this stop mechanism are fully disclosed 125 in the co-pending application above referred to and since any suitable stop mechanism may be employed in lieu thereof, a detailed description of this structure is believed to be unnecessary in this application. 130

The ring being operated upon by the grinding tools, is caused to rotate or spin rapidly by the action of the tools thereon and when the tools are withdrawn and the carrier is indexed, the spinning or rapid rotation of the ring just finished and the holder upon which it is mounted will continue. In order to stop this spinning so that the finished ring may be manually removed from the holder, I have provided a brake device, consisting, as shown in Fig. 3, of a leaf spring 55 fixed at one end upon a bracket 56 carried by the standard 29 and having its free end normally urged upwardly into the path of travel of the collars 39 of the ring holders by means of an adjustable set screw 57. It will be manifest therefore, that as the rotating holder is moved from position between the tools to the lower position illustrated in Figs. 2 and 3, the collar 39 thereof will be frictionally engaged by the brake spring 55, whereby the rotation of the holder will be stopped.

For the purpose of preventing accidental displacement of a ring from its holder, I have provided a guard or shield, disposed adjacent to the outer faces of the holders 37, this shield consisting of a flat plate 58 adapted to overlie three of the holders, but to leave the fourth one, which is most remote from the grinding tools exposed for the removal and replacement of rings thereon. This shield is attached to a carriage by an upper bracket 59 and is also secured along its lower edge to a stationary part of the frame. The shield is shaped at its edge adjacent the tools in conformity with the perimeter of the tool 12 so that the tool clears this inner edge in its movement, the shield, however, overlying a sufficient portion of the holder and ring to insure against accidental displacement of the ring from its holder.

It will be apparent from the foregoing that I have provided a ring grinding machine which automatically grinds both faces of a ring simultaneously, and during the grinding operation causes the ring to rapidly rotate or spin, thereby insuring an even and uniform finish to the ring. While one ring is being ground, the finished ring at the opposite side of the carrier may be removed and replaced by an unground ring whereupon the carrier is automatically indexed to bring the rings successively into co-operative relation with the tools. All of the operations are automatic so that the operator need only give his attention to the removal and replacement of the rings upon the holders as they are successively presented into accessible position.

It is believed that my invention, its mode of operation and many of its inherent advantages will be appreciated from the foregoing without further description, and it should be manifest that the structural de-

tails shown and described are capable of wide modification within the scope of the invention as defined in the following claims.

I claim:

1. In a ring grinding machine, the combination of means for simultaneously grinding both faces of a ring, a carrier, and rotatably mounted means on said carrier for rotatably supporting a ring in position to be operated upon and freely rotated by said grinding means. 70
2. In a ring grinding machine, the combination of ring grinding means, a freely rotatable ring holder, and means for bringing a ring on said holder and said grinding means in co-operative relation to thereby effect the grinding of said ring and the simultaneous rotation thereof by said grinding means. 80
3. In a ring grinding machine, the combination of a grinding tool, a carrier, and means rotatably mounted on said carrier for holding a ring in operative relation to said tool so that the ring will be rotated by said tool during the grinding operation. 85
4. In a ring grinding machine, the combination of a pair of opposed grinding tools, a carrier, a plurality of ring holders rotatably mounted on said carrier, and means for operating said carrier to position said holders successively in co-operative relation with said tools so that each ring is rotated with its holder during the grinding thereof by said tools. 90
5. In a ring grinding machine, the combination of a freely rotatable holder adapted to hold a piston ring, and means for acting on said ring to grind the faces thereof, said means causing the ring to rotate during the grinding operation. 100
6. In a ring grinding machine, the combination of a pair of opposed grinding tools, a carrier, a plurality of ring holders rotatably mounted on said carrier, means for actuating said carrier to move the rings on said holders successively into position to be operated upon by said tools, and means for stopping the rotation of each ring upon the completion of the grinding operation. 105
7. In a ring grinding machine, the combination of a pair of opposed grinding tools, a carrier, a plurality of ring holders rotatably mounted on said carrier, means for intermittently actuating said carrier to position the rings on said holders successively between said tools, means for moving said tools into contact with the positioned ring to effect the grinding of the faces thereof and simultaneously cause said ring to rotate, and means for stopping the rotation of said ring upon the completion of the grinding operation. 115
8. In a ring grinding machine, the combination of a pair of opposed grinding tools, a rotatable disc-shaped carrier, a plurality 120
9. In a ring grinding machine, the combination of a pair of opposed grinding tools, a carrier, a plurality of ring holders rotatably mounted on said carrier, means for actuating said carrier to move the rings on said holders successively into position to be operated upon by said tools, and means for stopping the rotation of each ring upon the completion of the grinding operation. 125
10. In a ring grinding machine, the combination of a pair of opposed grinding tools, a carrier, a plurality of ring holders rotatably mounted on said carrier, means for actuating said carrier to position the rings on said holders successively into position to be operated upon by said tools, and means for stopping the rotation of each ring upon the completion of the grinding operation. 130

- of ring holders each freely rotatable on said carrier, a gear wheel connected to said carrier, an operating shaft, a gear sector mounted on said shaft and meshing with said gear wheel whereby an intermittent rotative movement is imparted to said carrier, and means for automatically locking said carrier between successive movements thereof.
9. In a ring grinding machine, the combination of a rotatable carrier, a plurality of freely rotatable ring holders mounted on said carrier, a pair of opposed grinding tools, an operating shaft, means actuated by said shaft for imparting an intermittent rotary movement to said carrier to position the rings on said holders successively in co-operative relation with said tools, means controlled by said shaft for moving the grinding tools toward and from each other in predetermined relation to the movements of said carrier, and means for stopping the rotation of each holder after the ring carried thereby has been subjected to the action of said tools.
10. In a grinding machine, the combination of a rotatable carrier, a plurality of freely rotatable ring holders mounted thereon, means for intermittently imparting a rotary movement to said carrier, means for locking the carrier in the intervals between successive movements thereof, and means for stopping the rotation of each holder at a predetermined point in the travel of said carrier.
11. In a ring grinding machine, the combination of grinding apparatus, a carrier, a plurality of ring holders rotatably mounted on said carrier, means for operating said carrier to move the holders with the rings thereon toward and from said grinding apparatus in succession, and means independent of said holders for retaining the rings on the holders during their movement toward and from said grinding apparatus.
12. In a ring grinding machine, the combination of a grinding tool, a plurality of ring holders, means for moving said holders into co-operative relation with said grinding tool, and stationary means for retaining the rings on their respective holders.
13. In a ring grinding machine, the combination of a grinding tool, a plurality of ring holders, means for moving said holders in succession into co-operative relation with said tool, a stationary guard positioned in proximity to the path of travel of said holders for preventing displacement of the rings from said holders during the travel of the holders.

EDWARD B. GARDNER.
